United States Patent Office

Des. 214,177
Patented May 20, 1969

214,177

ROLLER BOARD

Larry J. Greer, 617 Oak, Emporia, Kans. 66801

Filed June 14, 1968, Ser. No. 12,368

Term of patent 14 years

Int. Cl. D12—11; D21—02
U.S. Cl. D34—15

FIG. 1

FIG. 2

FIG. 3

FIG. 4

FIG. 5

FIG. 6

FIG. 1 is a perspective view of a roller board showing my new design;

FIGS. 2 and 3 are respective opposite side elevational views;

FIG. 4 is a bottom view thereof;

FIG. 5 is a front view thereof; and

FIG. 6 is a rear view thereof.

I claim:

The ornamental design for a roller board, as shown.
